UNITED STATES PATENT OFFICE.

WILLIAM TEMPLIN, OF GLENELLYN, ILLINOIS.

DESIGN FOR A STAND FOR BOOKS.

46,458.

Specification for Design.

Patented Sept. 22, 1914.

Application filed February 24, 1913. Serial No. 750,424. Term of patent 7 years.

To all whom it may concern:

Be it known that I, WILLIAM TEMPLIN, a citizen of the United States, residing at Glenellyn, in the county of DuPage and the State of Illinois, have invented a new, original, and ornamental Design for Stands for Books, of which the following is a specification, reference being had to the accompanying drawing, forming part thereof.

The figure is a front prospective view of a stand of books showing my new design.

The top of upper portion of the stand is somewhat rectangular in shape, and so formed as to give a light, graceful appearance. The lower part of the stand is provided with legs having plain artistic outline. The stand may be made in various sizes suitable for supporting different kinds or shapes of books.

I claim:

The ornamental design for a stand for books, as shown and described.

WILLIAM TEMPLIN.
